(57) **CLAIM**

The ornamental design for a fitted coaster, as shown and
described.

DESCRIPTION

FIG. 1 is a plan view of a blank for a fitted coaster showing
my new design;

FIG. 2 is a perspective view of my design for a fitted coaster
in combination with a beverage container;

FIG. 3 is a front elevation view thereof;

FIG. 4 is a rear elevation view thereof;

FIG. 5 is a side elevation view of one side thereof;

FIG. 6 is a side elevation view of the opposite side thereof;

FIG. 7 is a bottom elevation view thereof;

FIG. 8 is a bottom perspective view of my design in
combination with a beverage container;

FIG. 9 is a view of a circular base of my design in an
assembled and folded configuration illustrated in even
broken lines;

FIG. 10 is another embodiment of my design in which the
sides of the fitted coaster are tapered from the top to the
bottom;

FIG. 11 is a perspective view of the fitted coaster from FIG.
10 assembled and in combination with a tapered beverage
container;

FIG. 12 is a front elevation view thereof;

FIG. 13 is a rear elevation view thereof;

FIG. 14 is a side elevation view of one side thereof;

FIG. 15 is a side elevation view of the opposite side thereof;

FIG. 16 is a bottom elevation view thereof;

FIG. 17 is a bottom perspective view of my design in
combination with a tapered beverage container;

FIG. 18 is another embodiment of my design in which a
surface of the fitted coaster includes corrugation;

FIG. 19 is a perspective view of the assembled fitted coaster
from FIG. 18 in combination with a beverage container; and,

FIG. 20 is another embodiment of my design in which the
